(57) **CLAIM**

The ornamental design for a furniture leg cover, as shown and described.

DESCRIPTION

FIG. 1 is a top, front, and right side perspective view of a furniture leg cover according to my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The dash-dash broken lines show portions of the furniture leg cover that form no part of the claimed design. Each of FIGS. 1–5 and 7 show a region of color along a bottom portion of the furniture leg cover. The vertical lines represent the color red.
